Primary Examiner — Messina L Smith

(57) **CLAIM**

The ornamental design for an herbal infusion machine, as shown and described.

DESCRIPTION

FIG. 1 is a top perspective view of an herbal infusion machine showing my new design;

FIG. 2 is a bottom perspective view thereof;

FIG. 3 is a front elevated view thereof;

FIG. 4 is a rear elevated view thereof;

FIG. 5 is a top plan view thereof;

FIG. 6 is a bottom plan view thereof;

FIG. 7 is a right elevated view thereof; and,

FIG. 8 is a left elevated view thereof.

The broken lines showing of a user interface in FIGS. 1 and 5, the broken lines showing of a power port in FIGS. 1, 3, 4, and 8, and the broken lines showing of a base in FIGS. 2 and 6 are included for the purpose of showing environmental structure and form no part of the claimed design.

1 Claim, 8 Drawing Sheets
